United States Patent Office

Des. 193,662
Patented Sept. 25, 1962

193,662

TELEPHONE HANDSET

David W. Hagelbarger, Morris Township, Morris County, N.J., assignor to Bell Telephone Laboratories, Incorporated, New York, N.Y., a corporation of New York

Filed Feb. 19, 1962, Ser. No. 68,873

Term of patent 14 years

(Cl. D26—14)

FIG. 1

FIG. 2

FIG. 1 is a perspective view of a telephone handset embodying my new design and showing the front face and one side of the handset;

FIG. 2 is a perspective view of the handset showing its rear face and the other side face;

FIG. 3 is a side view of my handset in inverted position; and

FIG. 4 is a front view of my handset.

The essential features of my new design reside in the portions shown in full lines. The partial broken line showing the cord is for illustrative purposes only.

I claim:

The ornamental design for a telephone handset, substantially as shown and described.
